ROBBERPROOF FIXTURE, LOCK, AND
ALARM FOR BANKS AND THE LIKE

Herbert H. Reger, Brooklyn, N. Y.

Application December 5, 1932, Serial No. 645,837

4 Claims. (Cl. 20—1.01)

This invention relates to a device for protecting money, valuable papers and other valuable articles, and particularly to an improved construction for banks or other institutions dealing in money or valuable securities wherein means are provided which are adapted to trap a bandit or robber and, if desired, give an alarm indicating his presence.

Another object of the invention is to provide for banks and the like fixtures or furniture which will segregate the bank into three zones connected and associated with means for locking the communicating doors between the respective zones at any time.

15 A further object, more specifically, is to provide furniture, locks and associated devices whereby any of the attendants in the bank may cause the locks to operate at any time silently so as to prevent the escape of any person whom it is desired 20 to hold within the bank.

25 An additional object is to provide a system of protection for banks and other financial institutions whereby raids by bandits during business hours can be frustrated, and in addition whereby the bandits may be captured before they leave the premises.

In the accompanying drawings—

30 Figure 1 is a horizontal sectional view through a building showing a schematic view of the arrangement of the furniture and certain other parts disclosing certain features of the invention;

Figure 2 is a vertical longitudinal section through Figure 1 approximately on the line 2—2;

35 Figure 3 is a side view of the locking mechanism shown in Figure 2 associated with each of the revolving doors illustrated in Figure 1, part of the doors being shown in section, and the lock, casing or housing being shown in section;

Figure 4 is a sectional view through Figure 3 40 on the line 4—4;

Figure 5 is a diagram showing substantially in top view certain of the locking features illustrated in Figure 3 and the door with which it is associated;

45 Figure 6 is a diagram of the wiring of the operating mechanism for the lock, the siren and certain other parts.

In many banks various means have been provided for the protection of the funds against 50 being stolen at night time, but during the day and during business hours there is very little protection provided except by watchmen or hired police officers. In case of a raid by a number of bandits the watchmen or police officers could easily be overcome and the clerks would then be

at the mercy of the bandits without a chance of locking the doors or otherwise trapping the robbers.

In the present invention means have been provided which is particularly adapted to be used during business hours for discouraging hold-ups or trapping bandits or robbers in case a hold-up is attempted. In order that this idea may be carried out special furniture, locks and the like have been provided so that, as illustrated in Figure 1, the bank is divided into three zones, namely, the vault zone, the access zone or area, and the public zone. The last two zones may be freely entered at any time by any of the patrons of the bank, and they may leave freely at any time while only the bank attendants will be found in the vault zone. By reason of dividing the bank into these three zones the bandits would be confined to either the public zone or to the access zone, and means have been provided for locking the doors to these two zones at any time by any of the attendants in the vault zone. Also means have been provided for sounding an alarm which when sounded will prevent the locking mechanism from becoming unlocked until the same has been released from a point exterior of the building, so that all persons in the bank under these circumstances will be confined in the building until the police or other authority arrives and operates the exterior releasing means.

In the accompanying drawings one embodiment of the invention has been disclosed and one diagram showing the various circuits involved, but it will be evident that other detailed structures and other circuits may be used provided the same general idea is maintained whereby the bandits will be discouraged and whereby they will be trapped before they can effect their escape.

As illustrated in Figure 1, there is provided a building 1 which may be of any desired kind, and in this building a vault 2 is provided, the same being of any desired structure. Adjacent vault 2 is a space 3 which has been designated as the vault area or zone. A bullet-proof partition 4 extends from one wall of the building 1 to the other and in this wall a number of windows 5 are provided. Back of these windows are arranged suitable partitions and other furniture 6 forming cages for the various tellers. Wall 4 is preferably provided with a single door 7 which is maintained locked at all times except when an attendant desires to enter or leave the area or zone 3.

Arranged adjacent area or zone 3 is an area or zone 8 which is known as the corridor or access zone. This zone is enclosed by the walls of the

building 1, wall 4 and wall 9, which last mentioned wall is provided with revolving doors 10 and 11. It will thus be seen that when any one passes through doors 10 or 11 and these doors are locked, the person will be trapped in zone 8 as he cannot pass through the bullet-proof door 7 and he cannot pass through walls 9 or either of the doors 10 or 11.

Adjacent zone 8 is public area or zone 12 which comprises all the space between wall 9 and the front of the building. The front of the building is provided with any suitable form of entrance doors 13 and, if desired, with windows 14. Windows 14 should be barred so that no one can enter or leave through them. A pair of revolving doors 15 and 16 with suitable casings are provided, said casings merging into walls 17 and 18 connected to the front of the building 1. These parts are formed of bullet-proof material but function ordinarily as regular revolving doors and casings so that the patrons can enter and leave freely. However, when any of the mechanism hereinafter fully described is operated, doors 15 and 16 as well as doors 10 and 11 will be quickly and silently locked so that no one can pass any of these doors. The locking action at first is only temporary and after a short time interval the locks will be silently and automatically released unless the circuit for the locking mechanism has been opened, which takes place upon the closing of a certain switch or button 19 (Fig. 6). When this button is closed temporarily the siren 20 will begin to function and the locking mechanism of the respective doors will not be released until the mechanism in the control box 21 arranged exterior of the building has been caused to function manually by a police officer or someone else. It will thus be seen that when the footpedal 22 is depressed until the contact points 23 and 24 have been engaged, means are caused to operate for locking the doors, which doors will remain locked until the time delay mechanism K is functioned. This mechanism may be set to function at one minute intervals, at five minute intervals or at other intervals as desired.

It will, therefore, be seen that in case pedal 22 is closed accidentally, the locks will be moved to locking position but will be released on the time interval set, as for instance, five minutes. However, if bandits are making a raid on the bank and switch 22 is closed, the locks are quickly moved to locking position and then one of the switch buttons 19 is pushed closing this circuit, whereupon the siren 20 will begin to function and the locks will be prevented from unlocking until released from the control box 21 as heretofore explained.

In Figures 3 and 4 details of the locking mechanism are disclosed, the same to be applied to all of the doors shown in Figure 1 except door 7 which is locked by a hand operated lock. Door 16 shown in Figure 3 is the usual type of revolving door and is provided with a central shaft 25 which is journaled in any suitable manner at both ends and at the upper end extending into the casing 26 where a journal spool 27 is provided. The locking disc 28 is rigidly secured by a pin or otherwise to shaft 25 and rests on the spool 27. The locking disc 28 is provided with four notches, namely, notches 29, 30, 31 and 32, as shown more particularly in Figure 5. It will be understood that notches 29 and 31 are diametrically opposite each other, and notches 30 and 32 are also diametrically opposite each other, thus dividing the disc 28 into four sections. A locking

bar 33 is adapted to move downwardly into either pair of notches, as shown in dotted lines in Figure 5, for locking disc 28, shaft 25 and the door against rotation. It will be noted from Figure 5 that the respective notches in disc 28 are much larger than the locking bar 33, whereby a limited movement of the door may be had so that when the locking bar 33 functions with the blades 34 of the door in the full line position shown in Figure 5, backward movement may be had until the parts assume the dotted position shown in Figure 5, whereby any one caught within the door may either escape outwardly or inwardly according to what part of the door he occupies. It will be seen that by this structure no one will be confined in the doors by the locking, but the lock will prevent any one from passing through the door after the same has been moved to a locked position. The locking bar 33 is pivotally mounted at the respective ends on the respective bell crank levers 35 and 36, said levers in turn being pivotally mounted at 37 and 38 so that the short arms 39 and 40 of the respective levers may be pivotally connected to the ends of the respective plungers 41 and 42 of the solenoids 43 and 44. When bar 33 is elevated or in its inoperative position, as shown in Fig. 3, both levers 35 and 36 are past dead center and, consequently, bar 33 is held positively in this position under the action of gravity. When conditions are as just described, the solenoids 43 and 44 are deenergized. When the locking solenoid 43 is energized, it will quickly draw up the plunger 41 and swing the bell crank lever 35 and parts associated therewith to the dotted position shown in Figure 3, whereupon bar 33 will fit into the openings 30 and 32, as shown in Fig. 5, thus locking the door against operation. It will be understood that solenoid 44 under these circumstances is deenergized and non-functioning. As soon as bar 33 has been moved downward to the locking position it remains in this position under the action of gravity after solenoid 43 has been deenergized.

To move bar 33 to an unlocking position it is necessary to energize the opening solenoid 44 and as soon as this is done the plunger 42 will quickly move upwardly swinging bell crank lever 36 to the full line position shown in Figure 3. This will also cause bell crank lever 35 to swing upwardly and locking bar 33 to move to an unlocked position as shown in Figure 3, causing the parts to assume the position shown in that figure. This action of locking and unlocking may occur as often as desired and will occur as often as solenoids 43 and 44 are energized and deenergized as just described.

In carrying out the invention the locking mechanism as just described is associated with each of the doors, as shown particularly in Figure 1, except door 7. When the foot switch 22 (Figure 6) is pressed and closed certain circuits will be closed, whereupon solenoid 43 will be energized, and the locking bar 33 for each of the doors will be lowered to a locking position. If nothing further is done besides temporarily closing switch 22, the mechanism herein described will after a certain time interval turn on current to solenoid 44 unlocking all the doors. It is to be understood that the doors are locked and unlocked silently so that if it is done accidentally, or intentionally, to confine a bandit, no one knows that the doors have been locked except the person who has closed the switch 22 and those employees who are in a position to see signal lights, until someone tries to pass through the

doors. However, means have been provided as hereinafter described which will sound an alarm and which will prevent the solenoid 44 from functioning until certain parts have been released by someone outside of the building.

It will be understood that a number of switch buttons 19 are to be provided. Preferably there is a switch button 19 and a foot switch 22 arranged in or adjacent each of the cages 6, and in addition a light, for instance, the light 45 shown in Figure 6 and hereinafter fully described, is provided. By arranging the parts as just described any one of a number of persons may cause the device to function. For instance, if a highway man is holding up one or two of the tellers, they will merely obey the bandit without attempting to close any of the switches while the bandit is in front of them. If any one who is not confronting the bandit sees what is happening, he will step on one of the foot switches 22, and if it is thought desirable, push switch button 19 to cause the siren 20 to sound and the locking mechanism shown in Figure 3 to be locked against release, except through the control box 21 on the outside of the building. If no one sees the bandit except the particular tellers facing the bandit, the device is left unmolested until the bandit leaves the tellers' windows and then the tellers themselves can close one of the foot switches 22 either before or after the bandits have passed through doors 10 and 11. Signal lamps 45 light whenever doors lock and warn all employees in position to see the signal light to be on their guard and investigate.

In order that the operation of the locking mechanism shown in Figure 3 and also the operation of the siren 20 and other parts may be more fully understood, attention is directed more particularly to the diagram of Figure 6. In this diagram the mechanism indicated by the letter "K" is a time delay mechanism which prevents the locking mechanism from opening until a certain time has elapsed according to the way the relay has been set.

When the foot switch 22 has been closed either intentionally or accidentally, current will first flow from source 46 over a circuit including contacts 23 and 24. It is to be understood that the source 46 is a source of current within the building, as for instance, a storage battery, a dry cell battery or, if desired, a small generator. By having the source of current within the building and protected, the bandits cannot make the device inoperative by cutting off the supply of current to the bank from an outside source. When the foot switch 22 has been closed, as just mentioned, current will flow from the source 46 to wire 47 and wire 48, but it cannot pass through this wire because the switch 49 is open, said switch being in the control box 21. This will make the wire or conductor 48 positive for its full length including contact 24. Current from contact 24 will pass through switch arm 22, contact 23, wire 50 to one end of the closing solenoid 51, and through closing solenoid 51 to wire 52 which is connected to the negative or return bus wire 53. Current will flow momentarily through this circuit to energize the closing solenoid 51 and thus move switch arms 54 and 52' to closed position so that other circuits will be closed thereby.

When the switch arm 54 is closed current will flow from the positive bus wire 48 through wire 55, electro-magnets 56, wire 57, wire 58, switch arm 54, wire 59, back to the negative bus wire 53, thus energizing the electromagnets 56. While

this is taking place current flows from the positive bus wire 60 through wire 61, wire 62, wire 63, switch arm 52', wire 64 to the closing solenoid 43 (see Fig. 6), wire 65, wire 66, back to the negative bus wire 53. As current flows in this last mentioned circuit solenoid 43 will function to move locking bar 33, as shown in Figure 3, downwardly to locking position, whereby all of the doors will be locked. When the circuit from the magnets 56 has been closed, said magnets will be energized and attract their armature 67 which is connected through suitable means including a spring 68 with switch structure 69 provided with resilient contact arms 70 and 71. The movement of armature 67 will swing contact arm 70 over until it engages contact 72 closing the circuit at that point. Arm 71 will not be moved over because of the bell crank lever 73 which is arranged so that arm 74 will prevent movement of the contact arm 71. Arm 74 is supported by a suitable pin 75. Bell crank lever 73 remains in position for holding contact arm 71 against functioning until the extension or abutment 76 on electric motor 77 moves over and strikes the leg 78 of the bell crank lever and swings this leg out of the path of movement of the contact arm 71, whereupon said contact arm will engage contact 79. It will be noted that the contact arm 71 is provided with a hook 80 which engages the resilient contact arm 81 when leg 74 has been moved out of the way and arm 71 moved under the action of armature 67. As hook 80 moves contact arm 81 it will break the engagement of this arm with contact 82 connected with wire 83. It will thus be seen that when the closing solenoid 51 is caused to function by the closing of the switch 22, switch arm 52' will close the circuit of closing solenoid 43 for actuating locking bar 33, and the closing of contact bar 54 will result in the energization of the magnets 56, motor 77 and light 45.

As the energization of the closing relay is only temporary, it is necessary to provide a second and more permanent closed circuit for the electromagnets 56. This is provided when the contact arm 70 engages contact 72. When this takes place current will pass from the positive bus wire 48 through wire 55, magnets 56, wire 57, wire 84 connecting wire 84', contact arm 70, contact 72, wire 85, wire 86, contact bar 87, wire 88, contact bar 89 and wire 90 back to the negative bus wire 53. Current will continue to flow in the last mentioned circuit after contact bars 52 and 54 have moved to an open position, thus maintaining the magnets 56 energized. As the closing relay 43 has been actuated, it will remain in its actuated position until positively moved therefrom, so that the opening of the circuit of this solenoid will produce no results.

While the contact bar 54 of the closing solenoid 51 is engaging its contacts, current will flow from the positive bus wire 60 through wire 91, lamp 45, wire 83, contact 82, contact arm 81, wire 84, wire 58, contact bar 54, wire 59 and back to the negative bus wire 53, thus causing the lamp 45 to function. When the bar 54 is moved to an open position current will flow through wire 91, lamp 45, wire 83, contact 82, contact arm 81, wire 84, wire 84', contact arm 70, contact 72, wire 85, wire 86, contact bar 87, wire 88, contact bar 89 and wire 90, back to the negative bus wire 53. Current flowing in this last mentioned circuit will cause the lamp 45 to remain functioning as long as motor 77 is energized. Also, since contact arm 70 engages contact 72 current will flow from the

positive wire 48, through wire 55, wire 92, electric motor 77, wire 93, wire 83, contact 82, contact arm 81, wire 84, wire 84', contact arm 70, contact 72, wire 85, wire 86, contact bar 87, wire 88, contact bar 89 and wire 90, back to the negative bus wire 53.

This will cause the motor 77 to function and to rotate the abutment 76. The speed of the abutment 76 may be varied so as to time the action 10 of the abutment 76 but cannot pass, the abutment thus striking leg 78 and bell crank lever 73 which will swing leg 78 out of the way of contact arm 71, whereupon said contact arm will quickly move over as it is resilient and under tension. Arm 71 15 will move until it engages contact 79 and also until the hook 80 causes the contact arm 81 to move away from contact 82. When this occurs certain parts will function to restore the device to its original position ready for another actuation. 20

It will be noted that current to motor 77 is turned off as the current to this motor is through contact 82. By the closing of contact 79 current will flow from the positive bus wire 60 through 25 wire 94, the windings of the opening relay 95, wire 96, contact 79, contact arm 71, contact arm 70, contact 72, wire 85, contact bar 87, wire 88, contact bar 89 and wire 90, back to the negative bus wire 53. Current flowing in the circuit just described is only temporary but will move the contact bars 89 and 97 to an open position, while closing the contact bar 100. Upon closing contact bar 100 current will flow from the positive bus wire 60 through wire 61, contact bar 100, 30 wire 101, through the windings of the opening solenoid 44, and thence through wire 66, back to the negative bus wire 53. When the solenoid 44 is energized, as shown in Figure 3, it will move the locking bar 33 back to its unlocked position. It 35 will be understood that this takes place in a very short time as, for instance, about one second and that contact bar 100 makes contact before contact bar 89 breaks contact.

While contact 100 is being held closed and the 40 opening solenoid 44 is functioning, contact bar 89 will be moved to an open position, as well as contact bar 97. When contact bar 89 is moved to open position it will deprive magnets 56 of current, whereupon armature 67 will be released and 45 contact arms 70 and 71 will be moved away from contacts 72 and 79, while contact 82 will be re-established. This will cause the parts to be in their original position before the actuation of switch 22. The parts are then in position to be 50 again actuated by switch 22 in case the same is closed either intentionally or accidentally. Where switch 22 is closed intentionally the various actions as above described take place except the last two, because switch button 19 is pressed and 55 this will result in parts being operated which will prevent the opening solenoid 44 from functioning and thereby prevent other parts from functioning. Upon closing switch button 19 after switch 22 has been closed current will pass from the 60 positive bus wire through switch 19, which is closed only temporarily, and thence to wire 102 to the respective contacts 103 and 104. As switch bars 49 and 105 are in open position no current will flow from wire 102. However, wire 106 will 65 be provided with current which will flow through this wire to wire 107, and thence through siren relay 108. From relay 108 current will pass through wire 109 to wire 59, and thence through wire 52 to the negative bus wire 53. As button 70 switch 19 is only held closed for a short time the 75

energization of the siren relay 108 will only be temporary and, consequently, bar 87 will be temporarily moved to open position and bars 98 and 99 will be temporarily moved to closed position.

As soon as bar 99 is moved to closed position 5 current will pass from the positive bus wire 60, through wire 61, bar 97, wire 110, bar 99, wire 107, siren relay 108, wire 109, wire 59 and wire 52, back to the negative bus wire 53. Current flowing in this circuit will maintain siren relay 10 108 closed so that the siren can function continuously until this circuit has been opened.

As soon as bar 98 has been closed and as long 15 as it is held closed, current will flow from the positive bus wire 60, through wire 61, wire 62, 15 wire 63, bar 98, wire 111 to the siren 20, and from thence through wire 112 to the negative bus wire 53. As bar 87 is held off its contacts current cannot pass through motor 77 or magnet 56 and, consequently, the locking bar 33 will remain in its 20 locked position and siren 20 will continue to sound. The siren cannot be turned off, nor can the opening solenoid 44 be caused to function at any point within the building, but can only be caused to function after the release box 21 has been opened 25 and the switches therein properly operated. As soon as the siren begins to sound, the outside watchman or one or more police officers can open the door 113 of the control box 21. This door carries switch bar 49, and when this door is opened 30 switch bar 49 immediately connects the contacts 103 and 48'. Also contact bar 105 is closed by the police officer. When bar 105 has been moved to closed position current will flow from wire 48 to contact bar 49, contact 103, contact 104, bar 105, 35 contact 114, wire 115, to the retaining relay 116, and thence through wire 117 to wire 88, through wire 88, bar 89 and wire 90 to the negative bus wire 53. Bar 120 is a holding contact to maintain positive current on relay 116 after push button 40 105 has been released.

This will cause retaining relay 116 to move the bars 118 and 120 to closed position. When bar 118 is closed it maintains current on "K" after 45 relay 51 opens. Current then flows from negative bus 53, wire 90, bar 89, wire 88, wire 117, bar 118, wire 85, contact 72, switch arm 70, thus maintaining negative current on "K" and keeping it in operation after button 105 has been opened. When bar 120 closes it serves to maintain positive current on relay 116 until the negative circuit is broken by bar 89 when relay 95 operates to unlock the doors. Current will also flow from contact bar 105 to wire 119, wire 50, through wire 50 in the circuit heretofore described, whereby 55 the closing relay 51 will be energized. This will cause the closing relay to be energized, but as the closing solenoid 43 has already functioned no additional results will be secured with respect to this solenoid. However, the closing of the bar 54 will 60 cause electro-magnets 56 to be provided with current and, therefore, cause the same to function, and as it functions the entire time delay mechanism "K" will function to eventually operate the opening solenoid 44 and restore the system to its 65 original condition. As soon as the time delay mechanism "K" has functioned, police officers or others may pass through the doors, also any one may pass out through the doors as they are unlocked.

As the opening relay 95 is caused to function it will deprive the siren relay 108 of current and thereby open the circuit at the siren so that it will cease to function. The bar 105 in the control box 21 is only temporarily closed and bar 49 70 75

is also only temporarily closed. As soon as lid 113 is opened, bar 49 is moved to closed position and immediately an officer or other person may close the contact bar 105 by hand. On releasing contact bar 105 it will move to open position, and upon releasing lid 113 this will swing to a closed position and open bar 49, but as these bars have closed circuits temporarily, the various other parts will function as described so that the siren 20 is turned off and the time delay mechanism "K" is caused to function to turn on current to the opening solenoid 44 after a certain specified time. Siren 20 is stopped by the operation of the door opening relay 95 opening bar 97.

As the solenoid 44 has functioned the time delay mechanism "K" is thrown out of operation and the parts are again in their original position, ready to function again if desired. It will be evident that the device may function as often as desired, and that when the foot switch 22 is closed and nothing else is done, the doors are locked for a short time and then automatically unlocked without any noise, or without any action on the part of any one. However, if the switch button 19 is closed during the time that the doors are locked they will remain locked and the siren 20 will begin to function and continue to function until the control box 21 has been caused to function as just described for opening the circuit to the siren and causing the time delay relay "K" to unlock the doors. The time delay mechanism "K" is an old and well known structure and, therefore, forms no part of the invention except in combination. This relay has been shown in diagram in Figure 6 without using all the details, but it will be understood that as the device is old and well known it will function as described so that the abutment 76 may move as fast or as slow as desired. It will also be noted that the arms 70 and 71 are offset in such a manner that they are overbalanced and will automatically move to the open position shown in Figure 6 when the armature 67 releases the same. Referring to Figures 3 and 4 it will be noted that locking bar 33 is fitted between two pairs of guiding and holding posts 33' so as to take the strain when the bar is in locked position and someone attempts to rotate the door. It should be noted that the foot switch 22 is a momentary contact switch and cannot be held in closed position. This makes it impossible for the doors to be released by pressure of this switch while the siren is sounding, because the circuit is broken at bar 87 of siren relay 108. Switch bar 49 is provided to sound siren if anyone tampers with the release box 21 and succeeds in opening the cover 113.

I claim:—

1. A lock for a rotatable door including a disc connected to the rotatable door, said disc having a plurality of diametrically opposite notches on one face, a locking bar adapted to move into and out of said notches for locking the disc and the door connected therewith, a bell crank lever pivotally connected to each end of said bar, means for pivotally mounting said bell crank lever, a sole-

noid operatively connected with one leg of each of said bell crank levers, one of said solenoids acting as an opening solenoid and the other as a closing solenoid, a source of current and a wiring system including said source of current and two circuits, one circuit being through said closing solenoid and the other being through said opening solenoid, a manually actuated switch for closing the circuit to the closing solenoid, and an automatically actuated time delay mechanism in the circuit of the opening solenoid. 10

2. A lock for a rotatable door including a notched member carried by said door, a locking bar adapted to move into and out of the notches in said notched member, a pair of bell crank levers connected with said bar for moving the bar, a solenoid for each of said bell crank levers for actuating said bell crank levers, said solenoids functioning at different times, a circuit for each of said solenoids including a source of current, and a switch for each of said solenoids. 15

3. A lock for a rotatable door including, a disc rigidly secured to said door, said disc having a plurality of pairs of diametrically opposite notches, a bar adapted to be moved into and out of said notches through a parallel motion, a bell crank lever pivotally connected at the respective ends of said bar, means for pivotally mounting said bell crank lever so that as said lever functions said bar will have a parallel motion as it is moved into and out of said notches, a solenoid for each of said bell crank levers, each of said solenoids having a core, said cores being pivotally connected to the respective bell crank levers, a circuit for each of said solenoids, each of said circuits including a source of current and a switch, one of said switches being a manually closed switch and the other being automatically actuated switch timed to close and then open at a spaced interval after the closing of the manually operated switch. 30

4. In a lock for a revolving door provided with a plurality of blades and a casing forming segments, a ring member having a notch for each of said blades, a locking bar adapted to fit into any pair of notches, said notches being longer than the locking bar is wide whereby when the locking bar is positioned in a locked position in said notches the ring and door may partly rotate a distance sufficient to permit one of said blades associated with each of said segments to move a sufficient distance away from the segments to permit a person to escape from that part of the doorway opposite the segments electrically, actuated means for moving said bar into said notches, 45 electrically actuated means for moving said bar out of said notches, a separate circuit for each of said electrically actuated means, each of said circuits including a source of current and a switch, one of said switches being a manually closed switch and the other being an automatically actuated switch timed to close and then open at spaced intervals after the closing of the manually operated switch. 50
